UNITED STATES PATENT OFFICE

152,238

DESIGN FOR A JACK-IN-THE-BOX DISPLAY FIGURE

Leslie V. Barofsky, Chicago, Ill.

Application April 29, 1947, Serial No. 138,676

Term of patent 7 years

(Cl. D1—2)

To all whom it may concern:

Be it known that I, Leslie V. Barofsky, a citizen of the United States, residing at Chicago, in the county of Cook and State of Illinois, have invented a new, original, and ornamental Design for a Jack-in-the-Box Display Figure, of which the following is a specification, reference being had to the accompanying drawing, forming a part thereof.

Fig. 1 is a face view of the jack-in-the-box display figure in open position, showing my new design.

Fig. 2 is a side view thereof.

Fig. 3 is a side view, showing the display figure in position before release.

The essential features of my design reside in the portion shown in full lines.

I claim:

The ornamental design for a jack-in-the-box display figure, substantially as shown and described.

LESLIE V. BAROFSKY.
